Wes. 1263

Samuel Morgan, of South Norwalk, Conn.

Assignor to

Himself and Chauncy Adams,
Letters Patent No. 1263, dated June 19, 1860.

The schedule referred to in these Letters Patent and making part of the same.

To all whom it may concern;

Be it known that I, Samuel Morgan, of South Norwalk, County of Fairfield and State of Connecticut, have invented or produced a new and original Pattern or Design for fire Shovel, and I do hereby declare that the following is a full and exact description of the same: and referring to the accompanying Photographic Views, in which the same letters indicate like parts in each of the figures.

In the accompanying drawings or Photographic Views

2

Dec. 1263.

Fig: 1. Shows a front elevation of my new, pattern or Design for fire
Shovel, &c. And

Fig: 2. Shows a back side view of the same.

a. is a flat curved end bottom, b. c. are flat, bent and slanting sides,
d. is a configuration of an enlargement of metal, with a handle shank e, arranged to
make a new pattern or design for a fire Coal or ash Shovel.

I claim a new plain pattern fire shovel having a handle shank
enlargement, configuration as illustrated and described -
